UNITED STATES PATENT OFFICE.

JOHN H. WILSON, OF ATLANTIC CITY, NEW JERSEY.

DESIGN FOR A COMBINATION CABINET, COSTUMER, AND SHAVING-STAND.

No. 39,271.

Specification for Design.

Patented April 21, 1908.

Application filed April 19, 1907. Serial No. 369,184. Term of patent 14 years.

To all whom it may concern:

Be it known that I, JOHN H. WILSON, a citizen of the United States, residing at Atlantic City, county of Atlantic, and State of New Jersey, have invented a new, original, and ornamental Design for a Combination Cabinet, Costumer, and Shaving-Stand, of which the following is a specification, reference being had to the accompanying drawing, forming a part thereof.

The figure is a perspective view of the combination cabinet, costumer and shaving stand embodying my design.

What I claim is:

The ornamental design for a combination cabinet, costumer and shaving stand substantially as herein shown.

JOHN H. WILSON.
